(57) **CLAIM**

The ornamental design for a display screen or a portion thereof with animated graphical user interface for a profit and loss table, as shown and described.

DESCRIPTION

FIG. 1 is a front view of a first image in a sequence for a display screen or a portion thereof with animated graphical user interface for a profit and loss table showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the transitional image sequentially transitions between the images shown in FIGS. 1-7. The process or period in which one image transitions to another forms no part of the claimed design.

The broken line showing the display screen or a portion thereof and remainder of the graphical user interface forms no part of the claimed design.
